Primary Examiner—Louis S. Zarfas*Assistant Examiner*—I. Simmons*Attorney, Agent, or Firm*—Lewis Anten, Esq.; Amedeo Ferraro, Esq.[57] **CLAIM**

The ornamental design for a spinal distractor, as shown and described.

DESCRIPTION

FIG. 1 is a side elevational view of the spinal distractor showing my new design, with all sides being the same; FIG. 2 is a front end view of the design of FIG. 1; FIG. 3 is a rear end view of the design of FIG. 1; FIG. 4 is a side elevational view of a second embodiment of the spinal distractor showing my new design, with the sides being the same;

FIG. 5 is a front end view of the design of FIG. 4;

FIG. 6 is a rear end view of the design of FIG. 4;

FIG. 7 is a side elevational view of a third embodiment of the spinal distractor showing my new design, with the sides being the same;

FIG. 8 is a front end view of the design of FIG. 7; and,

FIG. 9 is a rear end view of the design of FIG. 7.
